T. J. BOWYER,
SEWING MACHINE THREADING ATTACHMENT.
APPLICATION FILED JAN. 29, 1916.

1,239,765.

Patented Sept. 11, 1917.

UNITED STATES PATENT OFFICE.

THOMAS JAMES BOWYER, OF DULUTH, MINNESOTA.

SEWING-MACHINE THREADING ATTACHMENT.

1,239,765.

Specification of Letters Patent. Patented Sept. 11, 1917.

Application filed January 29, 1916. Serial No. 75,037.

To all whom it may concern:

Be it known that I, THOMAS J. BOWYER, a citizen of the United States, residing at Duluth, in the county of St. Louis and State 5 of Minnesota, have invented certain new and useful Improvements in Sewing-Machine Threading Attachments, of which the following is a specification, reference being had therein to the accompanying drawing.

10 My invention relates to improvements in sewing machine threading attachments, the primary object of which is to devise such an attachment which may be easily applied to any of the sewing machines as present on

15 the market.

Another object of the present improvement is to so construct the attachment that it is adapted to be attached to the pressure bar of the sewing machine and remain attached thereto, so that it will be available at all times when it is desired to use it.

A still further object of the present improvement is to devise such an attachment which is simple, compact, and inexpensive 25 to manufacture.

Other objects and advantages of the invention will be set forth in the following description and drawings, in which—

30 Figure 1 is a fragmentary perspective view of a sewing machine showing my improved threading attachment applied to the pressure bar thereof.

Fig. 2 is a top plan view of the attachment showing the pressure bar of the sewing machine in section.

35 Fig. 3 is a side elevation and sectional view taken on the line 3—3 of Fig. 2.

Fig. 4 is a bottom plan view of the attachment.

40 Fig. 5 is a horizontal sectional view of the attachment taken on the line 5—5 of Fig. 3.

Fig. 6 is a perspective view of the position of the needle, thread, and threading 45 hook of the attachment showing the said parts in separated relation.

Fig. 7 is an end elevation of the plate showing the guiding members for the reciprocating threading shaft.

50 Referring now to the drawings in detail in which like reference numerals designate similar parts throughout the several figures,

1 is a collar of such a design that it may be applied to the pressure bar of any sewing machine desired by merely enlarging or reducing the diameter thereof. After the

pressure foot of the sewing machine has been removed the collar 1 is slipped onto the pressure bar and held in its adjusted position by means of a set screw 2. This set 60 screw 2 holds one end of a band spring 3 which extends around one side of the collar and has its other end fitting within a horizontal slot 4 made in the collar 1. One side of the collar 1 is provided with an extension 5 which forms a bearing for an upright member 6 which passes therethrough and is held in position by means of the free end of the spring 3. The member 6 though of circular cross section, is provided with a 65 flattened portion 7 which when engaged by the spring 3 will hold the member 6 and parts carried thereby in position to thread the needle, as will be hereinafter described. The upper end of the member 6 is provided 70 with a horizontal extension 8 which serves as a handle and, being provided with a notch 9, which engages the shank of the sewing machine needle 10 forms a stop for the threading portion of the attachment, as 75 will be hereinafter set forth. The lower end of the member 6 carries a table like extension 11 which as shown herein is made integral therewith, but this extension 11 may be made separate and attached to the member 6 without departing from the invention herein. One side of the extension 11 is forked as at 12 to engage the needle 10 just above the needle eye. That part 13 of the fork which goes behind the needle is so 80 formed that it acts as a guide rest to hold the thread in position when threading the needle. The other portion 14 of the fork is flanged downward on one side in such a manner that the thread can be guided along 85 it to a point below the needle eye. A notch is also made at the base of this portion, which notch is numbered 15 on the drawing. This notch 15 is for the purpose of causing the thread when approaching the needle to 90 slip up and rest across the needle eye and in position to be engaged by a fine hook, hereafter to be described, which passes through and extends beyond the needle. The front side of the extension 11 is rolled over and 95 under so as to form bearings 16 in which is slidably mounted a small rod 17 which works back and forth carrying a fine hook 18 which is designed to pass through the needle eye and engage the thread 19 as is 100 clearly shown in Fig. 6. The rod 17 is provided with a notch 20 in the upper face 105

thereof within which fits a spring 21 having one end fastened within the lower end of the member 11 as at 22. This spring 21 both serves to keep the hook in alinement with the eye of the needle and especially to keep the rod 17 and fine hook 18 away from the needle. The outer end of the spring 21 is twisted at 23 to serve as a handle to move the rod and hook, so that the hook may be inserted through the needle eye and drawn back carrying with it the thread 19. 24 is a coil spring which encircles the upright member 6 and resting on the collar 1 tends to keep the upright member 6 raised with relation to the collar. Its purpose is to keep the horizontal portion 8 of the member 6 in contact with the needle holder of the sewing machine in case of careless adjustment.

20 To operate the device the attachment, through the medium of the horizontal member 8 serving as a handle, is swung around until the said handle springs into contact with the shank of the needle, the flattened portion of the upright member 6 and the band spring 3 serving to accomplish this result. The fork 12 of the extension 11 then embraces the needle 10 with the fine hook 18 carried by the rod 17 directly behind the eye of the needle. The hook bar is then shoved forward by pressure applied to the handle 23 until the hook 18 extends through the needle eye. The thread 19 is then brought under and across the fork 12 of the extension 11 and drawn backward until it slips into the notch 15 in the arm 14 of the fork 12 and under the hook 18 of the slidable rod 17. The appliance is then swung away from the needle carrying the thread through the needle eye.

Having thus described my invention, what I claim and desire to secure by Letters Patent is:

1. A threading attachment for sewing machines comprising a member attachable to the pressure bar of the sewing machine, a horizontally disposed L-shaped plate carried by the said member, said plate extending from a point at one side of the pressure bar forwardly and around in front of the needle,

the front edge of the said plate provided with a guideway, and a slidable member mounted in said guideway and having a hook on one end adapted to pass through the eye of the sewing machine needle. 55

2. A threading attachment for sewing machines comprising a member attachable to the pressure bar of the sewing machine, a horizontally disposed plate carried by the said member, the said plate having guideways on one edge thereof, a slidable member mounted in said guideways and having a hook on one end adapted to pass through the eye of the sewing machine needle, a spring having one end attached to the under side of the plate and engaging the top of the slidable member for normally holding the hook away from the needle. 60 65

3. A threading attachment for sewing machine needles comprising a member attachable to the pressure bar of the sewing machine, a horizontally disposed plate carried by the said member, said plate having a notch in one edge to receive the sewing machine needle, another edge of the said plate rolled to form a guide-way diametrically behind the said notch, and a slidable member mounted in said guideway and carrying means for threading the needle. 70 75 80

4. A threading attachment for sewing machine needles comprising a member attachable to the pressure bar of the sewing machine, a horizontally disposed plate carried by the said member, one edge of the said plate rolled to form a guideway, a slidable member mounted in the said guideway, a portion of the guideway cut away, a spring having one end attached to the plate and having a handle on the other end passing through the cut-away portion in the guideway and attached to the slidable member providing means for moving the slidable member between the limits of the cut-away portion. 85 90 95

In testimony whereof I hereunto affix my signature in the presence of two witnesses.

THOMAS JAMES BOWYER.
